UNITED STATES PATENT OFFICE.

EDITH WADE PRUITT, OF BALTIMORE, MARYLAND.

MARCEL HAIR NET.

Application filed February 17, 1922. Serial No. 537,265.

To all whom it may concern:

Be it known that I, EDITH WADE PRUITT, a citizen of the United States, residing at Baltimore, in the city of Baltimore and 5 State of Maryland, have invented a new and useful Marcel Hair Net, of which the following is a specification.

This invention relates to hair net constructions, and more particularly to hair 10 net constructions of the cap type.

The primary object of the invention is to provide a hair net of a construction to simulate Marcel waved or curled hair.

Another object of the invention is to 15 provide a device of this character including a pair of hair nets, strands of hair being formed with suitable waves positioned between the nets.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed, may be made within the scope of what is claimed, without departing from the spirit of the invention.

30 Referring to the drawing:

Figure 1 is a diagrammatic view of a hair net constructed in accordance with the present invention, one of the nets being broken away to illustrate the lower net.

35 Figure 2 is a sectional view through the hair net.

Referring to the drawing in detail, the reference character 5 designates the lower or inner net of the device, and the reference character 6 designates the upper or 40 outer net thereof, the nets being connected at their free ends, as clearly shown at 7.

These nets are constructed by folding a section of a net upon itself and connecting the side edges thereof.

45 Between the nets are arranged strands of hair indicated at 8, which may be of any desired color to meet the requirements of the user.

The strands of hair are suitably waved 50 or curled to meet the requirements of the wearer, before the same are positioned between the hair nets, so that when the hair nets are positioned on the head, the same will give the appearance of the person's hair 55 being marcelled.

It might be further stated that the nets should be formed as a cap, to closely engage the hair of the wearer to lend the appearance of the hair supported by the net, being 60 part of the hair of the wearer.

Having thus described the invention, what is claimed as new is:—

1. In a device of the character described, 65 an inner net and an outer net, strands of hair disposed between the nets, the strands of hair being waved or curled.

2. In a device of the character described, 70 an outer net and an inner net, strands of waved hair positioned between the nets, the ends of the net being connected.

3. In a device of the character described, 75 a net having a portion thereof folded upon itself, to provide an outer net and an inner net, strands of waved hair disposed between the nets, and said net having its free ends connected.

In testimony that I claim the foregoing as my own, I have hereto affixed my signature in the presence of two witnesses. 80

EDITH WADE PRUITT.
